UNITED STATES PATENT OFFICE.

DELIA MARTIN, OF FORNEY, TEXAS.

BEDCLOTHES-CLAMP.

No. 884,832.

Specification of Letters Patent.

Patented April 14, 1908.

Application filed July 19, 1907. Serial No. 384,621.

To all whom it may concern:

Be it known that I, DELIA MARTIN, a citizen of the United States, residing at Forney, in the county of Kaufman and State of Texas, have invented certain new and useful Improvements in Bedclothes-Clamps, of which the following is a specification, reference being had therein to the accompanying drawing.

My invention relates to improvements in clamping devices to be used upon beds for holding the clothes and covers thereon, and it consists in the novel features of construction, combination and arrangement of parts hereinafter fully described and claimed.

15 The object of the invention is to provide a simple, inexpensive and practical device of this character which may be readily applied to any bedstead and which will yieldingly hold the covers in place upon a child or other 20 occupant of the bed.

The above and other objects are accomplished by the improved construction illustrated in the accompanying drawings, in which

25 Figure 1 is a front elevation of my improved clothes clamp, showing it applied to the side rail of a bed; Fig. 2 is a vertical section through the same; and Fig. 3 is a horizontal section.

30 Referring to the drawings by numerals 1 denotes the side rail of a wooden bedstead having upon its inner face adjacent to its bottom a horizontal supporting ledge 2 formed with recesses or seats 3 for the cross slats 4; 35 and 5 denotes my improved clamp or fastener. The latter consists of a base or attaching member 6 and a spring actuated hinged member 7 provided with a jaw 8 to contact with a jaw 9 upon the member 6. This 40 attaching member 6 is in the form of a flat plate having its lower end forked or bifurcated to provide legs 10 which span one of the slats 4 and its seat 3, and have at their extremities right angularly bent feet 11 ap- 45 pertured to receive a screw or other fastening which secures them upon the top of the ledge 2. The main or body portion of the plate 6 is flat and is secured to the inner face of the side rail 1 by screws, or the like, passed 50 through apertures in outwardly projecting lugs 12 formed on the opposite sides of said plate. The stationary jaw 9 of the clamp is formed by bending the top of the plate 6 at right angles to form a horizontal portion 13 5 and then rolling the extreme end of said hori-

zontal portion to form a tubular bead, as clearly shown in Fig. 2.

Bent inwardly at right angles to the plate 6 at opposite points upon the middle of its side edges are apertured ears 14, the apertures in which are adapted to aline with apertures in similar ears 15 formed upon the pivoted plate or member 7. A pivot rod 16 is passed through the alining apertures in said ears and upon said rod is arranged a coil 60 spring 17 having one of its ends bearing against the plate 6 and its other end bearing against the lower end of the plate 7 to force the jaw 8 upon the upper end of the latter toward the stationary jaw 9. The top plate 7 70 has its lower end shaped to form a finger piece or handle 18 and its upper end 19 is preferably curved inwardly, as seen in Fig. 2 and formed with a horizontal slot 20 to provide the jaw 8. The slot 20 is of sufficient size to 75 permit the jaw 9 to pass through it and when the device is in use, the bed covers or clothes are inserted between said jaws, as indicated in dotted lines in Fig. 2. Upon reference to said figure it will be noted that this construction causes the body 9 to press the bed cover into the slot 20 and thus effectively hold it. If desired, said jaws may be faced with rubber, or the like, to reduce the danger of tearing or otherwise injuring the bed-clothes. 80

In use, the clamps are arranged upon the side rails of a bed at opposite points and any number of them may be employed. When four are used they are arranged adjacent to the four corners of the bed, and will effect- 90 ively hold the bed-clothes upon a child.

Having thus described my invention what I claim and desire to secure by Letters Patent is:—

1. A bed-clothes clamp comprising an attaching member in the form of a flat metal plate having its upper end bent at right angles and reduced at the extremity of its bent portion, said reduced portion being rolled to provide a bead or rib to serve as a stationary 95 jaw for the clamp, and a spring actuated movable member pivotally mounted upon the attaching member or plate and consisting of a metal plate having in its upper portion a slot or opening of greater size than said 100 bead or rib, said slotted portion of the pivoted plate being adapted to serve as the movable jaw of the clamp and to hold the bed-clothes in engagement with said bead or 105 rib, substantially as set forth.

2. The combination with the side rail of a bed having the slat supporting ledge and a slat upon the latter, of a clothes clamp having a flat attaching plate adapted to lie flat against the inner face of the bed rail, said plate being formed intermediate its end with apertured attaching ears to engage said bed rail and at its lower end with diverging legs to span the slat, the lower ends of the legs being formed with right angularly projecting apertured attaching ears to engage the slat supporting ledge, fastenings passed through said apertured ears and into the bed rail and
- its ledge, a stationary clamp jaw upon the upper end of said plate and a spring actuated member pivoted upon said plate and having at its upper end a movable clamp jaw to co-act with the stationary one, substantially as set forth. 15
- In testimony whereof I hereunto affix my 20
signature in presence of two witnesses.

DELIA MARTIN.
